UNITED STATES PATENT OFFICE

HUGO WIRTSCHAFTER, OF VIENNA, AUSTRIA

APPARATUS FOR PROJECTING DIAPOSITIVES

Application filed January 14, 1927, Serial No. 161,204, and in Austria January 20, 1926.

It has heretofore been customary in projecting diapositives intermittently that the diapositive in projection apparatus was quickly removed and the next diapositive 5 quickly inserted in order to make the period of interruption between two pictures on the screen as short as possible. The diapositives are usually changed by hand although mechanical means have also become known 10 whereby the diapositives are stopped in the projecting machine and then changed intermittently. These means, however, are bulky and complicated.

In contradistinction to the above presenting method, the method according to the invention is adapted especially for text diapositives, according to which the diapositives are passed by the window in a constant motion preferably automatically whereby the on- 15 looker receives the illusion that a moving text film is presented, as is usual where the texts are of great length. Moreover, the interruptions occurring with the known method for presenting diapositives and especially 20 in connection with long texts are obviated. It will also be possible for the onlooker to read the lines of the text and even texts of greater length repeatedly and with ease, whereas it has heretofore been necessary to 25 read hurriedly, because one did not know whether the diapositive would be changed before the last lines had been read. Finally, special attention is called to the advantage 30 of the constant movement of the diapositive, which is not effected by hand or by a motor but takes place automatically by the movement of the diapositives through their own 35 weight.

40 A modification of the method according to the invention wherein a chain of diapositives are formed, a diapositive constituting each link consists in keeping constant the difference in height or level between the places 45 where the chain links (diapositives) are deposited in order that the weight of the sinking piece of chain remains unchanged.

The accompanying drawings show two modifications of means for carrying out the 50 method in which:

Fig. 1 is a side view of a device for carrying out the invention.

Fig. 2 shows a series of diapositives articulated to each other.

Fig. 3 is a modified form of the invention; 55 and

Fig. 4 shows the form of diapositives in use with the device of Fig. 3.

The construction according to Figs. 1 and 2, which is very simple indeed, comprises a 60 chain or frame 1 for receiving the diapositives which are flexibly connected together. The chain is taken from one supply receptacle 4' by a drum 3 and moved past the window 2 of the projection apparatus to a depositing receptacle 4; the engagement between drum and chain is effected, for instance, by means of projections 6 and recesses 10.

The difference in height or level between the point removal and the point of deposit 70 is kept constant according to the invention, thus the length and weight respectively of the sinking and rising pieces of chain remain unchanged, which is advantageous for the uniform regulation of the speed of movement of the device.

This is done by making the receptacles 4 and 4' similar, each having a movable member supported on a spring 5. In this construction as weight is relieved in one receptacle and weight is added in the other the spring in each receptacle will move up and down respectively and proportionally.

In order to control the speed at which the chain 1 moves, a gear wheel 8a is provided 85 on the shaft of the drum and meshes with a gear wheel 8b carrying a flying vane 9.

The constant movement of the diapositives, thus provided for is temporarily interrupted to enable individual pictures of a series of 90 pictures to be viewed along while. For this purpose, the drum 3, driven by the falling chain, revolves and brushes directly or with its projections 6 against a stationary escape- 95 ment or arresting wheel 7 whereby the drum 3 is stopped and when driven by the chain, it turns the wheel 7 so that the projection 6 is released and the drum gradually revolves again with its full peripheral velocity. This 100 procedure is repeated during the next brush.

ing action, whereby the result is attained that the diapositive, which is in the window, is stopped temporarily, whereupon the further movement gradually commences.

5 This arresting means may be disconnected, for instance, by raising and lowering or by lateral displacement in order that the presenting of the diapositives may be effected as required with or without these temporary 10 interruptions.

The speed of movement of the wheel 7 may be governed by a flying vane 9 secured to transmission wheels 8, the wings of the flying vane being adjustable. The falling 15 speed is thereby kept uniform or constant while the picture is framed and if necessary the speed can be varied by such adjustment.

The contrivance according to Figs. 3 and 20 4 shows several successive diapositives superposed on one common carrier or support 11 (such as a frame or glass plate) formed of strips and moved past the window of the projecting apparatus.

For presenting texts of greater length, a 25 number of such strips 11 may be used in one and the same projecting apparatus, which is provided above and below the window with slides 12 and 12' respectively for the diapositives. Between the slides is provided as a 30 conveyor two chains 14 on opposite sides of the window adapted to move over upper and lower drums 20 and 20a. Each slide is formed of two rails on which the strips 11 having shoes 13 are supported. The strips 35 are provided with projections 15 for engaging with the chains. Each of these strips is secured to the top part of the support 11. When the strips are to be placed on the rails 12', they are released from engagement 40 with the chains.

According to the invention, there is provided at the end of the feed track 12 a releasing and arresting device, which is operated by the moving strip for the purpose of 45 effecting a release of the next strip. This arresting device is preferably formed by a lever 16 held before the foremost strips by a spring or the like and extending into the path of the descending strip in such a manner that 50 it is turned by the latter in time to permit the next strip to descend into engagement with the carrier chains. The lever 16 is also provided with an abutment, which, during the temporary turning movement thereof and 55 the release of a strip, engages before the next strip and thus retains the same.

The drum 20 is connected by gears 8a and 8b with a flying vane 9a, the same as the arrangement shown in Fig. 1 for controlling the 60 speed of movement of the chain incident to the operation of the apparatus.

What I claim is:

1. An apparatus for projecting diapositives in combination with an inclined track 65 located above the window and adapted to lead

the diapositives to a vertically movable endless chain, with means to bring the diapositives leaving the end of the track into engagement with the chain thus moving the latter by their weight.

2. An apparatus as claimed in claim 1 in which several successive diapositives are superposed on one common carrier, all carriers being arranged on the inclined track.

3. In an apparatus for projecting diapositives the combination with a projecting apparatus of an inclined track located above said apparatus adapted to receive a plurality of framed diapositives, an inclined track located below said projecting apparatus and adapted to receive said diapositives after passing through the projecting apparatus, and conveying means for the diapositives from the upper track through the projecting apparatus to be received by the lower track, 80 said conveying means including endless carriers adapted to receive and hold a diapositive from the upper track and to convey said diapositive through the projecting apparatus by the weight of the diapositives. 85

4. Apparatus for projecting diapositives, in combination, means to continuously move the diapositives through the apparatus, and means to temporarily retard the movement of the diapositives when the latter cover the 95 window of the projecting apparatus.

In witness whereof I have hereunto signed my name.

HUGO WIRTSCHAFTER.
